FIG. 1

FIG. 2

FIG. 3

FIG. 4

FIG. 5

FIG. 1 is a perspective view of the new design for a locating stop for work to be machined or the like;

FIG. 2 is a rear elevational view thereof as viewed in FIG. 1;

FIG. 3 is a right-hand elevational view of FIG. 1;

FIG. 4 is a left-hand elevational view thereof; and

FIG. 5 is a bottom view of FIG. 1.

The locating stop for work to be machined or the like is of the type used on milling machines, vertical or horizontal, and other machines where workpieces have to be readily and repeatedly located, in which regard the broken line disclosure of a clamping device and workpiece is shown for illustrative purposes only.

I claim:

The ornamental design for a locating stop for work to be machined or the like, as shown and described.
